Specification for Design.

Patented Nov. 30, 1915.

Application filed September 18, 1915. Serial No. 51,488. Term of patent 7 years.

all whom it may concern:
Be it known that I, CARL ROSENBERGER, a citizen of the United States, and a resident of the city, county, and State of New York, have invented a new, original, and ornamental Design for Rings, of which the following is a specification, reference being had to the accompanying drawing, forming part hereof.

Copies of this patent may be obtained for five cents each, by addressing the "Commissioner of Patents, Washington, D. C."

Figure 1 is a front elevation of a ring, showing my new design; Fig. 2 is a side elevation of the same; Fig. 3 is a rear elevation of the same, and, Fig. 4 is a plan view of the same.

I claim:

The ornamental design for a ring, as shown.

CARL ROSENBERGER.
